RAILWAY DRAFT APPLIANCE

Filed June 1, 1926

UNITED STATES PATENT OFFICE.

WILLIAM McCONWAY, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

RAILWAY DRAFT APPLIANCE.

Application filed June 1, 1926. Serial No. 112,974.

My invention relates to draft appliances for railway cars, and more particularly to the type wherein the coupler is designed to swing laterally so as to assume appropriate angular positions when the car to which it is attached passes around curves.

The primary object of the invention is to afford a construction providing simple, efficient and durable means for pivotally connecting a car coupler to a draft yoke or its equivalent, the structural features of the mechanism being such as to permit the car readily to be hauled to its destination in case the straps or links of the yoke device should become broken in service.

The principal feature of the invention consists in employing, in association with a car coupler, a yoke device including a block provided with trunnion sockets and having a forwardly opening slot for receiving a draft key adapted to extend through slots in the draft sills of a car, the coupler being formed with integrally attached trunnions extending into the corresponding sockets of the block and being provided, in alinement with the said slot in the block, with a rearwardly opening slot for receiving a draft key, the rear end of the slot in the block and the forward end of the slot in the coupler being spaced apart a greater distance than the width of the key longitudinally of the coupler so as to afford clearance between the forward end of the coupler slot and the neighboring edge of the key.

Other features of the invention pertaining to advantageous details of construction and arrangements of parts will hereinafter appear and be pointed out in the claims.

In the drawings illustrating preferred embodiments of the invention,—

Figure 1 is a view, partly in plan and partly in horizontal section, of a draft appliance embodying the invention, the rear end of the yoke device being omitted.

Figure 2 is a detail view, partly in elevation and partly in vertical section, of the construction shown in Fig. 1.

Figure 3 is a view, partly in plan and partly in horizontal section, of a modified form of the invention.

Figure 4 is a detail view, partly in elevation and partly in vertical section, of the structure shown in Fig. 3.

Figure 5 is a view, partly in plan and partly in horizontal section, of another modified form of the invention.

Figure 6 is a detail side elevational view of the construction shown in Fig. 5.

In the drawings, 1 indicates the head and 2 the shank of a car coupler. As shown, the 60 coupler shank is formed with vertically extending cylindrical trunnions 3 which are preferably cast integral therewith. The rear end 4 of the coupler shank is curved cylindrically concentric with the axis of the trunnions 3 to form a bearing for transmitting 65 buffering forces to the means associated with the coupler for actuating a cushioning unit. Between the trunnions 3 the shank of the coupler is formed with a transversely extending rearwardly opening slot 5 for receiving a draft key 6.

The coupler is associated with a yoke device 7 which may be of the usual form having elongated slots 8 and yoke straps or arms 9. 75 The coupler is pivotally connected to the yoke through the intervention of a block 10 and the standard draft key 6. The block is formed as an integral member having vertically aligned cylindrical sockets 11 for receiving the 80 corresponding trunnions 3, the latter being cast in place in the said sockets. Between the trunnion sockets and extending to the rear thereof the block 10 is fashioned with a forwardly opening slot 12 for receiving the 85 draft key; and in advance of the rear end of said slot the block is cylindrically curved, as indicated at 13, so as to form a buffering bearing 90 for cooperating with the correspondingly curved bearing face 4 at the rear end of the coupler shank. The rear end face 14 of the trunnion block is adapted to engage the forward follower or other part of the cushioning unit (not shown) located between the arms of the yoke device; and if desired the 95 block may be provided with a recess or pocket 15, thus adapting it to be used in conjunction with the forward follower of the well known Farlow draft gear attachments. The slots in the coupler, trunnion block and yoke de-

100 vice are in horizontal alinement and the draft key which passes therethrough is designed also to extend through slots in the draft sills of the car in the usual manner. The closed rear end of the slot 12 in the draft 105 block and the closed forward end of the slot

5 in the coupler are spaced longitudinally of the mechanism so as to afford clearance between the forward end of the slot in the coupler and the neighboring edge of the draft key, 5 thereby permitting the coupler to swing laterally without binding upon the key.

It will be perceived that the construction permits the rear edge of the draft key to be located at a proper distance from the inner 10 end of the block 10 while yet preserving the strength of the draft key and yoke device, and that it also permits the pivotal axis of the coupler to be so positioned with respect to the yoke as to afford the former a wide range 15 of lateral swinging movement.

It will also be noted that should the yoke straps 9 become broken the draft appliance will not become detached from the car and that therefore the latter may be hauled to 20 its destination.

As shown in the modified form of the invention illustrated in Figs. 3 and 4, the draft block may be formed as a member 16 of somewhat increased width so as to cooperate with 25 the links or bars 17 of the well known and widely used Farlow draft attachments. Other features of this form of the invention are preferably identical with those heretofore described and therefore are indicated by 30 corresponding reference numerals.

Figs. 5 and 6 show a modified form of the invention in which the trunnion block member 18 and the straps or arms 19 of the yoke device are integrally united, thus rendering 35 it normally unnecessary to employ the draft key 6. But the car coupler and the block 18 of this form of the device are slotted so as to permit the draft key to be inserted therethrough and through the car sills, thereby enabling the car to be hauled to its destination 40 in the event of the breaking of a yoke strap 19. This form of construction is advantageous in that by cutting off the straps of a broken yoke the coupler and trunnion block 45 18 may be employed in association with the so-called universal attachments or with the well known Farlow attachments. Except as heretofore described, the structure shown in Figs. 5 and 6 embodies features of construction 50 already described, and accordingly like reference numerals have been applied to corresponding parts.

I claim:

1. A railway draft appliance comprising 55 a car coupler, and means pivotally associated therewith for actuating a cushioning unit, said means including a block provided with trunnion sockets, the coupler having integrally attached trunnions extending into the corresponding sockets of the block, and the coupler and block being slotted to receive a draft key, the slot in said coupler opening rearwardly, and the slot in said block extending rearwardly beyond the trunnions.

60 2. A railway draft appliance comprising a

car coupler, and means pivotally connected thereto for actuating a cushioning unit, said means including an integral block formed with trunnion sockets, the coupler having integrally attached trunnions extending into the corresponding sockets of said block, and the coupler and block being slotted to receive a draft key, the slot in said coupler being open at its rear end, the slot in said block being closed at its rear end, and said end of the slot in the block and the forward end of the slot in the coupler being spaced longitudinally to afford clearance between the forward end of the slot in the coupler and the neighboring edge of the key.

3. A railway draft appliance comprising a car coupler, and means for transmitting draft forces therefrom to a cushioning unit, said means involving a yoke device having key receiving slots therein, a block pivotally connected to said coupler, and a key operatively connecting the block and yoke device, the block being formed with oppositely disposed trunnion sockets and having a forwardly opening key slot extending between said sockets, the coupler being integrally provided with trunnions extending into the corresponding sockets of the block and also being formed with a rearwardly opening slot extending between the trunnions, and a draft key extending through the slots in said yoke device, block and coupler, the forward end of the slot in the coupler being in advance of the neighboring edge of said key.

4. A railway draft appliance comprising a car coupler, and means for transmitting draft forces therefrom to a cushioning unit, said means involving a yoke device formed with slots for receiving a draft key, a block provided with oppositely disposed trunnion sockets and having a forwardly opening slot in alignment with the slots of the yoke device, said block and yoke device being relatively movable longitudinally, said coupler having integrally attached trunnions extending into the corresponding sockets of the block and being provided with a rearwardly opening slot between the trunnions, and a draft key passing through the slots of the yoke device, block and coupler.

5. A railway draft appliance comprising a car coupler, a yoke device, said coupler and yoke being relatively movable longitudinally of the car in buffering, and means for pivotally connecting said coupler and yoke device involving a block, means for pivotally connecting said coupler and block, and a draft key extending through said block and adapted to transmit draft forces to the yoke device, said key and block having transversely extending coacting bearing faces disposed rearwardly of said means for pivotally connecting the coupler and block, and the rear end of said block being adapted to engage a cushioning unit.

6. A railway draft appliance comprising a car coupler having a rearwardly opening key slot therein, a yoke device, and means for pivotally connecting said coupler and yoke device involving a block having a key slot therein, means for pivotally connecting said coupler and block, and a draft key extending

through said slots and adapted to transmit draft forces to the yoke device, said key having bearing engagement with the block rearwardly of said coupler. 10

In testimony whereof I affix my signature.
